UNITED STATES PATENT OFFICE.

WILLIAM FRANCIS MEEK, OF TAMPICO, MEXICO.

BARREL-PROTECTOR.

1,384,704.

Specification of Letters Patent. Patented July 12, 1921.

Application filed October 19, 1920. Serial No. 417,949.

To all whom it may concern:

Be it known that I, WILLIAM FRANCIS MEEK, a citizen of the United States, and resident of Tampico, Tamps, Mexico, have 5 invented a new and Improved Barrel-Protector, of which the following is a full, clear, and exact description.

This invention relates to a barrel protector, and aims to provide a device of this nature, 10 not necessarily limited to receptacles of this class, which device provides a slightly different construction over that in my co-pending application, Serial Number 417,950 filed Oct. 19, 1920.

15 In connection with the above identified application, it is pointed out that there are some instances in which it might prove desirable to utilize a protector having a slightly different form of body bracing portion, and 20 with this in view the present invention contemplates the provision of a slightly modified form of body bracing portion.

Reference is had to the attached sheet of drawings as representing one practical embodiment of my invention, and in which—

Figure 1 is a sectional side view taken along the line 1—1 of Fig. 2.

Fig. 2 is a sectional plan view taken along the line 2—2 of Fig. 1.

30 Fig. 3 is a side view of one of the units forming a part of my improved protector, and

Figs. 4 and 5 illustrate the head protecting sections forming a part of each unit.

35 My invention contemplates the provision of two units adapted to coöperate together to provide the finished protector, and in view of the identical nature of each of these units, I shall describe only one, and then specifically and subsequently bring in the coöperation of the same.

It will now be noted that the reference numeral 10 indicates what is conveniently termed the head protector, and which is 45 adapted to lie adjacent the head of a receptacle 11, for the purpose of preventing an escape of the contents of the receptacle, even should a small puncture occur within the head of the same.

50 The body bracing protecting or bracing member is now provided, and this member preferably includes a plurality of body portions 12, 13, 14 and 15, each presenting an exterior face conforming in the form shown, 55 to an arc of a circle, having its center, as the interengaging center portions of braces 16

and 17, connecting the sections 12 and 14, and 13 and 15 respectively, together. These interengaging portions of the braces 16 conveniently include a recessed part in one of its faces, and at a point intermediate its extremities, the recessed parts of both of the braces 16 and 17 being adapted to coöperate together to permit of the firm interengaging of these members, as has been illustrated in Fig. 1.

The side edges of the body bracing portions, and heads, are inclined so as to conform to the interior contour of the receptacle with which my improved protector is 70 associated, and in this connection it will be noted that the staves 18 connecting one pair of the body bracing member with the head protector 10, are also curved to lie against the inner face of the receptacle wall to 75 strengthen the same.

It will of course be seen that in view of the fact that the pair of body portions connected with the head protector 10 carry the second pair of these portions, that one of the entire 80 body bracing members is connected to one of the heads by this expedient.

It will now be seen, reference being had to Fig. 3, that a groove 19 is formed in the outer face of one of the body portions, this 85 groove preferably forming a part of those body portions not directly connected to the head 10. Staves 18 of the second unit are now arranged to lie slidably in the grooves 19, and it will be understood that by this 90 construction that the entire protector is longitudinally extensible.

Thus, I have provided a protector more particularly contemplated for use in connection with a barrel, but not necessarily limited 95 for use with this type of receptacle, but which shall embody extremely simple construction, in that the body bracing members of the same may readily be assembled within the interior of the receptacle, and by means of which protector the entire body and heads of the receptacle will be strengthened, so that any damage incident to transportation will be reduced to a minimum, thereby preventing a loss of the contents of 100 the receptacle.

Obviously numerous modifications of structure might readily be resorted to without in the least departing from the spirit of my invention, which I claim as—

110 1. A protector for receptacles, adapted to be arranged within and extending through-

out the entire length of the same, including in combination a pair of body bracing portions adapted to contact with the inner face of the receptacle, each of said bracing portions including a plurality of body portions, each comprising substantially one fourth of a complete circle, and means for connecting said bracing members one to the other.

2. A protector for receptacles, adapted to 10 be arranged within the same, including in combination a pair of body bracing portions adapted to contact with the inner face of the receptacle, each of said bracing portions including a plurality of body portions each 15 comprising substantially one fourth of a complete circle, and slidable means for connecting said bracing members one to the other.

3. A protector for receptacles, adapted to 20 be arranged within the same including in combination a pair of body bracing portions adapted to contact with the inner face of the receptacle, each of said bracing portions including a plurality of body portions each 25 comprising substantially one fourth of a complete circle, and head protectors for said receptacles forming a part of the protector, said body bracing members being connected one to each of said head protector portions.

30 4. A protector for receptacles, adapted to be arranged within the same including in combination a pair of body bracing portions adapted to contact with the inner face of the receptacle, each of said bracing portions including a plurality of body portions each 35 comprising substantially one fourth of a complete circle, head protectors for said receptacles forming a part of the protector, certain of the body portions being connected 40 to each of said heads.

45 5. A protector for receptacles, adapted to be arranged within the same, including in combination a pair of body bracing portions adapted to contact with the inner face of the receptacle, each of said bracing portions including a plurality of body portions each 50 comprising substantially one fourth of a complete circle, and head protectors for said receptacles forming a part of the protector, and staves having one of their ends secured to said head protectors, the opposite end of said staves being connected to certain

of the body portions of said bracing members.

6. A protector, adapted to be arranged 55 within a receptacle, said protector including a pair of units each comprising a head protector portion and a body bracing member, said body bracing member comprising a plurality of body portions, each presenting an outer edge conforming to one fourth of a complete circle, braces extending between pairs of opposed body portions, said braces being adapted to contact at their point of intersection, and being formed with means for providing a joint at this point, and means for connecting said head protector and body bracing member of each unit, one with the other.

7. A protector, adapted to be arranged 60 within a receptacle, said protector including a pair of units each comprising a head protector portion and a body bracing member, said body bracing member comprising a plurality of body portions, each presenting an outer edge conforming to one fourth of a complete circle, braces extending between pairs of opposed body portions, and being formed at its point with a cutout portion 65 at their contacting faces, said cutout portions being adapted to coöperate together to provide a joint for connecting all of the body portions together, and means extending between said body bracing member and head protector of each unit for connecting the 70 same together.

8. A protector adapted to be positioned 75 within a receptacle, said protector including a pair of units, each of said units comprising a head protector, body bracing member 80 and staves extending between said head protector and body bracing member for connecting the same together, each of said bracing members including a plurality of body portions, said staves being connected to 85 certain of said body portions, other of the body portions being formed with grooves, all of said body portions being connected together, the grooves in the face of the bracing member being adapted to slidably accommodate the staves of the second unit, whereby to render the protector longitudinally extensible.

WILLIAM FRANCIS MEEK.
